UNITED STATES PATENT OFFICE.

DARIUS E. NEWELL, OF NEW YORK, N. Y.

DESIGN FOR A PULLEY.

SPECIFICATION forming part of Design No. 25,718, dated June 30, 1896.

Application filed July 13, 1895. Serial No. 555,937. Term of patent 14 years.

To all whom it may concern:

Be it known that I, DARIUS E. NEWELL, of New York, in the county and State of New York, have produced a new and original Design for Pulleys, of which the following is a specification.

My design relates to pulleys such as are used with belting.

My design consists in a configuration for the periphery of a pulley, and comprises a number of cavities in the face of the pulley, arranged in rows, those of alternate rows being opposite the spaces between those of intermediate rows.

The accompanying drawing is a view of a pulley embodying my design.

A designates the pulley.

B' B² designate rows of cavities in the face of the pulley. It will be seen that the cavities of each row are opposite the spaces between those of the next row.

What I claim as my design, and desire to secure by Letters Patent, is—

The design for a pulley, substantially as shown and described.

In testimony whereof I have signed my name to this specification in the presence of two subscribing witnesses.

DARIUS E. NEWELL.

Witnesses:

D. C. NEWELL,
E. W. HEDDEN.
